COMBINED CIGARETTE AND MATCH
DISPENSER

Archie A. Wolf, Louisa, Ky.

Application September 24, 1932
Serial No. 634,758

7 Claims. (Cl. 312—78)

This invention relates to improvements in dispensing devices and relates particularly to a dispensing device for cigarettes and matches.

The primary object of the present invention is to provide a device for attachment to the windshield of a motor vehicle or to be mounted at any other place within a motor vehicle or other structure, which by the operation of a single element thereof will simultaneously eject or dispense a match and a cigarette.

Another object of the invention is to provide a dispensing device of the above described character which is of a neat and compact nature and which will occupy a minimum of space and is, therefore, especially suited for use in a motor vehicle.

A still further object of the invention is to provide a device for simultaneously dispensing a single cigarette and a single match in which novel means is employed for effecting this operation.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:—

Figure 1 is a view in front elevation of the dispenser embodying the present invention;

Figure 2 is a view in rear elevation of the dispenser;

Figure 3 is a vertical sectional view taken on the line 3—3 of Figure 1 and showing the mode of mounting the dispenser upon a body such as the glass of a motor vehicle windshield;

Figure 4 is a sectional view taken substantially on the line 4—4 of Figure 1;

Figure 5 is a view of the dispenser with the cover thereof open showing the cigarette compartment and a portion of the ejecting mechanism;

Figure 6 is a transverse sectional view taken substantially upon the line 6—6 of Figure 1;

Figure 7 is a view looking at the motor vehicle windshield and showing the elements attached to the glass for facilitating the mounting of the dispenser thereon;

Figure 8 is a sectional view taken substantially upon the line 8—8 of Figure 7.

Referring now more particularly to the draw-

ings wherein like numerals of reference indicate corresponding parts throughout the several views, the numeral 1 indicates a body upon which the present device is shown mounted and represents a portion of a motor vehicle windshield.

The present device is designed particularly for application to a motor vehicle windshield so that the driver of the motor vehicle may readily obtain a match and cigarette without moving into any position which would be likely to cause him to lose control of the vehicle such, for example, as shifting the position of his body in order to put his hand into a pocket. With the present device the driver can maintain a firm grip upon the steering wheel of the motor vehicle while employing the other hand to remove the cigarette and match from the dispenser. While the device is shown as applied to a glass body which is described as being a windshield of a motor vehicle it is to be understood that it is not to be confined to such use but may be mounted in any position and upon any body where it will be found serviceable.

The mounting of the cigarette and match dispenser which is indicated as a whole by the numeral 2 is effected by means of the three supporting elements, two of which are indicated by the numeral 3, while the third is indicated by the numeral 4. The elements 3 each consist of a disk 5 to one face of which is attached a centrally apertured lug 6. This disk is cemented or otherwise suitably secured to the surface of the body 1 with the lug arranged so that the aperture thereof will be vertically disposed and the supporting members 3 are arranged in the side by side spaced relation shown in Figure 7.

The third supporting device which is indicated by the numeral 4 is disposed at a lower elevation than the devices 3 and upon a line passing midway between the devices 3 as is also shown in Figure 7. This lower device comprises a disk 7 from the face of which extends a lug 8 through which a vertical passage 9 is formed. A slot 10 is formed in the forward end of the lug 8 and enters the passage 9 as shown in Figures 3 and 8 and pivotally mounted in this slot 10 upon the vertical pivot pin 11 is a flat latch 12 which is normally urged to swing inwardly to extend across the passage 9 as shown in Figure 8, by a spring 13. The outer end of the latch 12 is formed to provide the terminal 14 by means of which a hold may be obtained on the latch in order to turn it.

The dispenser 2 comprises an elongated relatively broad flat receptacle having a bottom or

back portion 15 and a front or cover portion 16. The back portion of the receptacle consists of the back wall 17 and the top, bottom and side walls 18, 19 and 20, respectively, the side walls 5 at their lower ends being connected together and connected with the bottom wall by the relatively 10 low front wall 21. The back wall 17 of the back portion of the receptacle is provided with the longitudinally extending slot 22 in which moves an arm 23 carried by a follower 24. The outer 15 end of this arm has attached thereto a disk 25 which moves against the rear surface of the back wall 17 and prevents the arm from coming out of the slot 22. The follower 23 as shown in Figure 5 extends across the interior of the back portion of the receptacle and is of a length substantially equal to the interior width of this portion.

This follower rests upon the uppermost one of 20 the cigarettes 26 when the same are placed in the receptacle, the lowermost one of the group of cigarettes lying upon the bottom wall 19 thereof.

One side wall 20 of the bottom portion of the 25 receptacle is provided with an opening 27, the bottom of which is flush with the top or inner surface of the bottom wall 19 and this opening is of sufficient size to permit of the passage therethrough of the bottom one of the group of cigarettes in the receptacle.

The wall 21 has formed therein a slot 28 which 30 is enlarged at one end as indicated at 29 and which enlarged end is located adjacent the side wall 20 opposite that in which the opening 27 is formed and this slot extends a short distance in the direction of the opening 27 and is disposed in a horizontal plane which passes through the center of this opening. Above this slot 28 there is attached to the wall 21 a rib 29', the purpose of 40 which will be hereinafter described.

Upon the rear face of the back wall 17 there are fixed two lugs 30 which are spaced apart a distance equal to the spacing of the lugs 6 of the supporting elements 5 and each of these receptacle lugs 30 carries a downwardly directed pin 31 which is designed for extension through the aperture in a supporting lug 6. At the lower end 45 of the receptacle back upon the rear face and longitudinal center thereof there is fixed the lug 32 from which extends downwardly below the bottom of the receptacle the relatively long pin 33 which is tapered at its free end to facilitate its ready insertion into the aperture of the lug of the bottom supporting member 4.

The taper of this pin enables the pin to shove the latch finger outwardly and when this pin has moved the proper distance the latch finger will engage in the notch 34 which is formed transversely thereof.

Hingedly attached to one side of the back 50 15 of the receptacle by the hinges 35 is the cover 16. This cover has the top wall 38 and the side wall 39 at the front edge. As shown, the front wall 37 of the cover portion is of materially less length 65 than the back portion 15, terminating at its lower edge in the plane of the top edge of the wall 21 of the back portion.

Disposed in spaced relation with the front wall 37 at the lower part thereof is an auxiliary front wall 40 which is attached to the wall 37 by the side flanges 41 and 42. This auxiliary wall extends downwardly below the edge of the wall 37 and when the cover of the receptacle is closed overlies the wall 21 of the back portion. A bottom wall or flange 43 extends across the inner

face of the auxiliary wall 40 between the side flanges 41 and 42 and slidably mounted upon this flange 43 and held in place by the yoke 44 is a reciprocable bar 45. One end of this bar 45 normally positions against the inner face of the flange 41 and at this end there is formed integral therewith the laterally projecting flat finger 46. This finger is constricted slightly adjacent its point of joinder with the bar 45 as indicated at 46' in Figure 4 and this constricted portion extends through the slot 28 and slides therein when the cover 16 is closed upon the back portion 15 of the receptacle and when the bar 45 is shifted in one direction in the manner hereinafter described.

At the inner end of the bar 45 is an upstanding arm 47 which passes upwardly along the inner face of the auxiliary wall 40 and joins one end of a horizontal upper bar 48 which overlies the lower bar 45 as illustrated in Figure 1 and which terminates in the upwardly projecting finger 49. This finger 49 extends upwardly through a slot 50 which is formed longitudinally of a flange 51 which extends transversely of the inner face of the auxiliary wall 40 adjacent the top edge thereof and this flange forms the bottom for a match receptacle which is indicated as a whole by the numeral 52. The rear wall of the receptacle 52 is indicated by the numeral 53 and integral with this rear wall are forwardly projecting top and side walls 54 and 55 respectively. Hingedly attached to the side wall 55 which is upon the same side of the dispenser as the hinges 35 is a cover 56 for the match receptacle. The hinges 57 connect this cover with the adjacent side wall 55 and the cover is provided with a top flange 58 and a free edge flange 59, these flanges 58 and 59 overlying the adjacent walls 54 and 55 as illustrated in Figures 1 and 3. Resilient fasteners 60 attached to the back portion of the match receptacle engage over the free edge of the cover 56 when the same is closed to hold the cover in this position and at the central part of the free edge of the cover an extension 61 is formed which provides means by which the cover can be 120 grasped to be opened.

The cover 56 is provided with the vertical slot 62 through which extends a stem 63 which carries upon its outer end the head 64 and upon its inner end a follower 65 which is relatively heavy and which normally forces the matches 66 downwardly against the wall 51 which forms the bottom of the match receptacle. As shown in Figure 1 the side wall 55 of the match receptacle opposite the side adjacent which the hinges 57 are located is offset slightly so that the finger 49 may extend up into the receptacle behind the lowermost one of the matches 66. The side wall 55 of the receptacle to which the cover therefor is hinged is provided with an opening 67 through which a match may be ejected. This opening is at the same side of the dispenser as the opening 27 in the side wall of the bottom portion of the cigarette receptacle so that when the bars 45 and 48 are shifted toward these openings the finger 46 upon the lower bar 45 will eject a cigarette through the opening 27 and the finger 49 which is upon the bar 48 will move in the slot 50 and eject a match through the opening 67. In order to effect the operation of these 145 ejector bars the vertical arm 47 has attached thereto the reduced portion 68 of a key 69 which portion of the key extends from the outside of the auxiliary wall 40 through the horizontal slot 70 which is formed in this wall. At the inner 150

side of the wall 40 there is disposed a coil contracting spring 71 which has one end secured to the side flange 41 of the auxiliary wall and has its other end attached to the vertical arm 47.

5 This spring through its constant tendency to contract pulls upon the arm 47 and thus retains the fingered ends of the bars 45 and 48 in position respectively behind a cigarette and a match.

When the cover 16 of the cigarette receptacle 10 is in closed position the flange 29 upon the outer face of the wall 21 positions over the ejector bar 45 and thus serves as an additional guide for this bar to insure its movement in a straight path.

15 Upon the outer face of the cover 56 of the match receptacle there are mounted the two spaced guides 72 between which is removably held a sheet of emery paper or any other suitable rough material 73 which will provide a striking surface for the match.

20 The cover or top 16 for the cigarette receptacle is held in closed position by the spring latch 74 which is attached to the bottom 15 and projects upwardly across the free edge of the cover as 25 shown in Figures 1 and 2. In order to provide the proper clearance for the extension of the finger 47 into position behind a cigarette the lower part of the wall 20 at the free side of the bottom portion 15 is pressed outwardly slightly 30 as indicated at 75.

From the foregoing description it will be readily apparent that the present match and cigarette dispenser may be readily mounted in working position upon a windshield by the use of the 35 supports 3 and 4 and when so mounted a cigarette and match may be readily obtained simply by shifting the ejector bars 45 and 48 through the manipulation of the key 69.

It will also be readily seen that either the 40 cigarette container or the match container may be opened for the ready replenishment of the contents thereof and the entire dispenser may be readily removed from position or placed in position as required.

45 Having thus described the invention, what is claimed is:—

1. In a dispenser of the character described for dispensing elongated objects, a relatively flat receptacle having a cover, an opening formed through one edge wall of said receptacle adjacent the bottom thereof for the discharge of an article therefrom, a second relatively flat receptacle carried by said cover and having an article discharging opening through one edge wall thereof, and means carried by said cover which is operative when the cover is closed to engage an end of an article in each receptacle and eject the articles through said discharge openings.

2. A dispensing device of the character described, comprising a flat receptacle having a removable cover, a relatively low wall disposed at one end of said receptacle and having a slot therein extending transversely of the receptacle, said wall being covered by said cover, the said 60 receptacle having an article discharging opening through one edge wall, a bar member mounted upon the inner side of said receptacle cover for reciprocation transversely thereof, a finger carried by said bar at one end and adapted to extend into said slot when the receptacle cover is closed, means operable from the front of said cover for reciprocating said bar to effect the ejection of an article from the receptacle through the discharge opening, and resilient means normally maintaining said bar in one position.

3. A device for simultaneously dispensing cigarettes and matches, comprising an elongated flat receptacle, a hinged cover for said receptacle, said cover comprising a main wall portion of less length than the receptacle and an auxiliary wall portion, said auxiliary wall portion being disposed in a plane offset from the plane of the main cover and cooperating with the main cover to completely close the receptacle, a second flat receptacle carried by said cover above said auxiliary wall portion and having a slotted bottom, said second receptacle having an article discharging opening in one edge wall, said first mentioned receptacle having an article discharge opening in one edge wall, a pair of bar members mounted for reciprocatory movement transversely of the under side of said auxiliary wall, a finger member carried by each of said bar members, one of said fingers being designed to engage behind an article in said first receptacle to eject the same through the discharge opening thereof and the other of the fingers being designed to extend into the second mentioned receptacle through the slotted bottom for ejecting an article therein through the discharge opening thereof, and means for simultaneously shifting said bar members.

4. A combined cigarette and match dispenser, comprising an elongated relatively flat cigarette receptacle having a hinged cover, a second relatively flat receptacle mounted upon the face of the hinged cover of the first receptacle and having a bottom wall provided with a longitudinal slot, each of said receptacles having a side edge wall provided with a discharge opening, a pair of connected bar members disposed in spaced relation and mounted upon said cover for simultaneous movement transversely thereof, a finger carried by one of said bar members and extending into the second mentioned receptacle through the slotted bottom of the same, a finger carried by the other of the bar members and extending into the first mentioned receptacle when the cover is closed and engaging a cigarette at one end, said bar members when shifted transversely of the cover effecting the discharge of a cigarette and a match from the receptacles, resilient means normally maintaining the bar members in inoperative position, and means common to said bar members for effecting their simultaneous movement.

5. An article dispenser, comprising a receptacle having an outlet through which the articles are ejected, a second receptacle mounted before a wall of the first receptacle and having an outlet through which the articles are ejected, a slidably mounted member disposed beneath one receptacle and before one face of the other receptacle and having a pair of fingers one disposed vertically for extension into the overlying receptacle and the other extending laterally into the other receptacle, each of said fingers engaging an end of an article in the receptacle into which it extends, means permitting movement of each finger in its receptacle toward the adjacent outlet, and means for shifting the fingers simultaneously.

6. An article dispenser, comprising a receptacle having an outlet, a second receptacle secured to and carried by a wall of the first receptacle and having an outlet, said second receptacle having a slotted bottom wall, a member mounted for sliding movement across the wall of the first receptacle to which the second receptacle is secured, a finger carried by said member and disposed in the slotted wall of the second receptacle for en-

gagement behind an article therein, a second finger carried by said member and extending laterally therefrom into the first receptacle for engagement behind an article therein, and means carried by said member for effecting its movement in a direction to cause the ejection by said fingers of an article from each of the receptacles into which they extend.

7. A cigarette and match dispenser, comprising a unitary structure having a match chamber with an outlet and a cigarette chamber with an outlet, a closure for each chamber whereby access may be had to either chamber without opening the other, an injection finger slideable in a recess

in the bottom of one chamber for the ejection therefrom of one of the articles therein and initially engaging over the end of the article, an injection finger slideable in a side wall slot of the other chamber for the ejection therefrom of an article therein and initially engaging over the end of the article, connecting means between the fingers for moving the same simultaneously for the simultaneous ejection of two articles, and actuating means for the fingers, one of said chambers being carried upon and moving with the closure of the other chamber.
